UNITED STATES PATENT OFFICE.

BOLESLAW HOLOWNIA, OF SYRACUSE, NEW YORK.

KNIFE.

1,296,805.

Specification of Letters Patent. Patented Mar. 11, 1919.

Application filed December 10, 1918. Serial No. 266,053.

To all whom it may concern:

Be it known that I, BOLESLAW HOLOWNIA, a citizen of Russia, residing at Syracuse, in the county of Onondaga and State of New York, have invented certain new and useful Improvements in Knives, of which the following is a specification.

The primary object of the invention is the provision of a knife adapted for paring fruits and vegetables by hand, the depth of cut being readily adjustable for rendering the same uniform.

A further object of the invention is to provide a paring knife having an adjustable guard whereby the thickness of the severed portion of the article operated upon may be uniform and regulated at will, the structure being light in weight and possessing great utility.

20 A still further object of the invention is the provision of a guard for any form of cutting blade so arranged as to be easily and quickly secured in its adjusted position suitable for the required operation, the device 25 being simple in construction and easy to manufacture.

With these general objects in view, the invention consists of the novel combination and arrangement of parts hereinafter fully 30 described in connection with the accompanying drawing and in which like reference characters designate corresponding parts throughout the several views.

Figure 1 is an elevational view of the invention showing one flat side of the cutting blade with the guard illustrated by dotted lines in its operative position.

Fig. 2 is an elevational view of the invention looking toward the cutting edge.

40 Fig. 3 is an elevational view of the opposite side of the invention from that shown in Fig. 1.

Fig. 4 is a transverse sectional view taken upon line IV—IV of Fig. 1, on an enlarged 45 scale.

Fig. 5 is an enlarged detail plan view of a portion of the invention as shown in Fig. 1.

Fig. 6 is an enlarged transverse sectional view taken upon line VI—VI of Fig. 1, and 50 Fig. 7 is an enlarged longitudinal detail sectional view taken upon line VII—VII of Fig. 1.

Referring more in detail to the drawings, I have illustrated my adjustable cutting 55 guard in connection with a knife having a blade 10 and handle 11, it being understood,

however, that the invention may be employed upon other forms of knives and cutters.

The blade 10 has a longitudinal cutting 60 edge 12 while a disk 13 is eccentrically pivoted within a side slot 14 at the point of connection between said blade and handle by means of a suitable pin 15. The free end of the blade 10 is provided with a curved 65 point 16 serviceable for extracting cores or seeds as well as being convenient for various other uses. A roller 17 is concentrically journaled adjacent the free end 18 of the blade 10 within a side notch 19 of the blade 70 by means of a pin 20.

The pins 15 and 20 are positioned in axial alignment with each other and a substantially U-shaped guard 21 connects the disk 13 with the roller 17 whereby the guard 75 may be swung into close proximity to the cutting edge 12 when desired as best illustrated in Fig. 6 of the drawings as well as swung away from said cutting edge in an arcuate path upon the journaling pins 15 80 and 20. It will be seen that the guard 21 will be positioned at all times parallel to the cutting edge 12.

A retaining screw 25 is longitudinally carried by the handle 11, being threaded through 85 lugs 22 upon one side of the handle while the free end 23 of the screw is rounded for frictionally engaging the disk 13 when the guard 21 is positioned at the desired adjustment. A knurled head 24 upon the outer 90 free end of the screw 25 outwardly of the handle 11 is readily grasped for turning the screw 25 for either engaging the disk 13 or releasing the same.

The complete operation of the invention 95 will be apparent from this detail description thereof, the guard 21 being secured in adjusted position by the screw 25 for cutting the desired thickness of material, the handle 11 is grasped and the blade 10 is employed for forcing the cutting edge 12 through the article operated upon, such as a potato or an apple which is being pared by the operator. The guard 21 may be swung rearwardly of the blade 10 when not desired for use, leaving the cutting edge 12 free and clear for employment in cutting articles while the guard 21 may be swung farther around and secured in adjustment 100 adjacent the opposite side of the cutting edge 12 from that illustrated in Fig. 4, although at such times the guard is incap- 105 110

ble of positioning as near the edge 12 as when positioned at the opposite side thereof, this being by reason of the fact that the end portions 26 and 27 of the guard do not project radially from the disk 13 and roller 17 respectively. By retaining the guard 21 at different distances from the cutting edge 12, different thicknesses of cut may be readily made by means of the blade 10 in the hand 10 of an operator.

What I claim as new is:

1. A device of the class described comprising a blade having a cutting edge, a disk eccentrically journaled adjacent one end of the blade, a guard for said edge attached to the disk and adapted for adjustment at different distances from said edge and adjustment retaining means for the disk.

2. A knife comprising a blade and a handle with a cutting edge at one side of the blade and slots in the opposite side of the knife from said cutting edge, a disk eccentrically journaled within the slot at the handle end of the blade, journaling means in the other slot in axial alinement with the journaling axis of the disk and a guard for the cutting edge carried by said disk and journaling means.

3. A knife comprising a blade and a handle with a cutting edge at one side of the

blade and slots in the opposite sides of the knife from said cutting edge, a disk eccentrically journaled within the slot at the handle end of the blade, journaling means in the other slot in axial alinement with the journaling axis of the disk, a U-shaped guard connecting said disk and journaling means adapted for positioning at different distances from said cutting edge and adjustment retaining means for the disk carried by the handle of the knife.

4. A knife comprising a blade and a handle with a cutting edge at one side of the blade and slots in the opposite sides of the knife from said cutting edge, a disk eccentrically journaled within the slot at the handle end of the blade, journaling means in the other slot in axial alinement with the journaling axis of the disk, a U-shaped guard connecting said disk, lateral projections upon said handle, a retaining screw positioned longitudinally of the handle threaded through said projections with the inner end of the screw adapted for seating upon the disk when in its adjusted positions and a knurled handle member upon the outer end of the screw outwardly of the free end of the handle.

In testimony whereof I affix my signature.
BOLESLAW HOLOWNIA.
